UNITED STATES PATENT OFFICE

GEBHARD C. BOHN, OF ST. PAUL, MINNESOTA

REFRIGERATOR CLOSURE

Application filed April 28, 1928. Serial No. 273,548.

The present invention relates to a refrigerator door construction.

In the manufacture of refrigerator doors where an enameled metal shell is used on the exterior of the door, it is desirable, in order to avoid the use of screws, penetrating this exterior shell, to crimp the edges of the metal to engage the interior door construction of wood and insulating material. Since 10 it is impracticable to bend the enameled metal after enameling, or to enamel it with the inner door construction in place, it is necessary to use some sort of collapsible construction for the inner door portion so that it may 15 be set up in engagement with the crimped edges of the enameled metal shell.

An object of the present invention is to make a collapsible door structure which may be set up within an enameled metal shell to 20 have interlocking engagement with the edges thereof.

In order to attain this object, there is provided a plurality of interlocking frame units insertible within the crimped edges of an 25 enameled metal plate, and having a rigid super-structure permanently secured thereto to hold the interlocking parts against displacement.

These features of the invention will be more 30 fully brought out in the following description and the accompanying drawings, wherein:

Figure 1 is a view in perspective of the inner side of the completed door unit.

Figure 2 is a view in elevation of the inner side of the door unit with a metal inner plate removed therefrom to show the construction of the inner frame portion of the door.

Figure 3 is a sectional, perspective view 40 through the door structure shown in Figure 1.

Figure 4 is a view in perspective of one of the interlocking frame units.

Figure 5 is a view in perspective of one of the superstructure frame units.

Figure 6 is a view similar to Figure 2, with the end members of the super-structure frame work removed; and

Figure 7 is an enlarged view similar to 50 Figure 6 with one of the longitudinal inter-

locking frame members slid to a position to free the end interlocking frame units.

Referring to the drawings in detail, an enameled plate 1 is formed with the edges thereof bent upwardly and inwardly as at 55 2 to engage an interlocking frame work composed of end pieces 3 and 4 and side pieces 5 and 6. The end pieces are constructed as shown in Figure 4, with a groove 7 cut longitudinally of the inner edge thereof. The 60 end pieces 4 are formed with a tongue 8 extending outwardly from the end at which these end pieces 4 abut with the other end pieces 3. The other end pieces 3 are each formed with a corresponding groove, not 65 shown, to receive the tongue 8. The outer longitudinal edges and also the outer ends of the end pieces 3 and 4 are similarly formed, having a shoulder 9 cut therein at a height 70 to fit beneath the upwardly and inwardly turned edges 2 of the metal plate 1. A second shoulder 10 may also be cut in these pieces at the height of the upper surface of the tongue 8 to fit the door opening, not shown. The longitudinal members 5 and 6 75 are formed with a tongue similar to the tongue 8 of the end members 4 projecting outwardly from both ends thereof. The outer edges of these members are formed with shoulders similar to the shoulders 9 and 10 of the members 4 for the purposes previously set forth for these shoulders.

The super-structure of the door comprises longitudinal members 11 and 12, one of which is affixed adjacent the inner edge of 85 each of the longitudinal frame members 5 and 6. The ends of these longitudinal members 11 and 12 are cut down as at 13 to form a lap-joint with the end super-structure members 14 and 15, shown in Figure 5. 90

In assembling the device, the end members 3 of the collapsible framework are placed as shown in Figure 7 and the longitudinal members 5 and 6 are inserted with the end tongues thereof engaging the grooves on the 95 inner side of the end frame members 3. The combined width of the longitudinal members is necessarily somewhat less than the length of one of the end members 3 so that the other end members may be inserted, 100

as shown in Figure 7, inwardly of the already inserted end members 3. The tongue 8 of the end members 4 may then be slidably moved into engagement with the groove in 5 the already installed end members 3. When the end members are installed and slidably moved outwardly so as to engage the upwardly and inwardly bent edge 2 of the metal plate 1, the longitudinal member 6 10 may be slidably moved laterally with the tongue on either end thereof engaging the grooves on the inner edge of the end members until the shoulder 9 of the longitudinal member 6 rests beneath the upwardly and inwardly turned edge of the metal plate 1. The longitudinal super-structure members 11 and 12 are then securely fastened to the longitudinal interlocking frame members as by nails, not shown, and the transverse 20 super-structure frame members 14 and 15 may then be affixed in position, as shown in Figure 2, the super-structure thus binding the interlocking frame securely together and preventing displacement of any of the members thereof. The customary insulation as 25 at 16, 17, and 18 in Figure 3 may then be inserted and an inner metal facing plate 19 may be secured in position as by means of nails 20. Strips 21 may then be secured to 30 the frame work to cover the edges of the inner metal plate 19 to complete the door structure.

I claim:

1. A refrigerator door, comprising a metal 35 plate having a recess about the edge thereof, an interlocking frame comprising a pair of interlocking units positioned on opposite edges of said plate to engage the recess on the edge of said metal plate, and a pair of 40 intermediate frame members having interlocking engagement with said end members and laterally slidable to lie adjacent each other, the combined width of said intermediate members being less than the length of 45 one of the end members.

2. A refrigerator door comprising a metal plate having a recess about the edges thereof, a pair of end frame members shorter than the width of said door plate, said members 50 having beads on the outer edges thereof to enter said recess and having a groove on the inner side and end thereof, a pair of longitudinal frame members insertible between said end members when in position in said plate, 55 the combined width of said longitudinal members being less than the length of one of said end members, each of said longitudinal members being provided with a bead on the outer edge thereof to enter said recess and 60 having tongue and groove engagement with the inner edge of said end members, and a second pair of end members similar to said first end members and having tongue and 65 groove engagement therewith, one of said longitudinal members being adapted to slide

transversely of said second end members to a position adjacent the edge of said door plate.

3. A refrigerator door having a metal plate with a recess about the edges thereof, a collapsible frame comprising a pair of end members having a bead on their outer edges and ends, and a groove on their inner edges, and a pair of longitudinal members mounted between said end members and having 70 tongue and groove engagement therewith, said longitudinal members being slidable laterally to be positioned both on one pair of end members, leaving the other pair free for removal.

In testimony whereof I affix my signature.
GEBHARD C. BOHN.
